UNITED STATES PATENT OFFICE.

JOHN C. FORSTER, OF PITTSBURG, PENNSYLVANIA.

DESIGN FOR A GAS-STOVE.

SPECIFICATION forming part of Design No. 36,173, dated December 16, 1902.

Application filed October 16, 1902. Serial No. 127,610. Term of patent 7 years.

To all whom it may concern:

Be it known that I, JOHN C. FORSTER, a citizen of the United States, residing at Pittsburgh, in the county of Allegheny and State of Pennsylvania, have invented and produced a new, original, and ornamental Design for Gas-Stoves, of which the following is a full, clear, and exact description, reference being had to the accompanying drawing, forming part hereof, in which the invention is shown in perspective.

As shown in the drawing, the leading or material feature of my design consists in an open-front body 2 of rectangular outline mounted on base 3 and surmounted by upper portion 4 of similar outline, having in its top surface the open-work panel or grating 5. Within the open front of the body is

a series of fiber-covered vertically-projecting arched ribs 6, terminating at their lower ends 20 at ledge 7, formed with a winding or serpentine line of perforations 8. At the sides of and paralleling ribs 6 are curved columns 9, reaching from ledge 7 to upper portion 4. The opposite ends of upper portion 4 have corresponding ornamental panels, one of which is shown at 10. 11 designates the ornamental feet.

I claim—

The ornamental design for a gas-stove, as herein shown and described.

In testimony whereof I affix my signature in the presence of two witnesses.

JOHN C. FORSTER.

Witnesses:

J. M. NESBIT,
ALEX. S. MABON.
